Application January 17, 1946, Serial No. 641,758

8 Claims. (Cl. 170—160.21)

1

This invention relates to the control of blade-angle of a variable pitch propeller and more particularly a propeller having hydraulically operated blade-adjusting torque units operated by fluid-pressure means located entirely within the propeller hub.

An object of the invention is to provide means forming a part of the propeller hub assembly for effecting adjustments in accordance with the setting of a device located external to the hub and connected mechanically with said means. The device may be one which is under direct manual control by the pilot or it may be an engine-speed-responsive or engine-torque device mounted, for example, on the engine frame.

In the disclosure and embodiment of the present invention this object is accomplished by providing distributing valve units located within the propeller hub and comprising a valve body having an inlet port connected with a pump also located within the hub and connected with a reservoir of hydraulic fluid provided by the hub. The valve body has distribution ports connected with the torque units and a movable valve member for controlling the distribution port. The valve member is under control by the device external to the hub for causing the valve to move away from neutral position to effect a blade angle change and the valve is under control by the blades for returning the valve to neutral position when the blades have been adjusted to the angle determined by the device.

Further objects and advantages of the present invention will be apparent from the following description, reference being had to the accompanying drawings wherein a preferred embodiment of the present invention is clearly shown.

In the drawings:

Fig. 1 is a perspective view, somewhat diagrammatic, showing a propeller and a hydraulic system which includes the present invention;

Fig. 2 is a fragmentary view partly in section on the line 2—2 of Fig. 1;

Fig. 3 is a fragmentary sectional view on the line 3—3 of Fig. 2;

Fig. 4 is a sectional view on line 4—4 of Fig. 2;

Fig. 5 is a fragmentary sectional view on line 5—5 of Fig. 2; and

Fig. 6 is a fragmentary view in the direction of arrow 6 of Fig. 5.

The blade-angle torque units with which the present invention is adapted to be used may be, for example, like those disclosed in the patents to Blanchard and MacNeil Nos. 2,307,101 and 2,307,102, issued January 5, 1943. Fig. 1 shows

somewhat diagrammatically a propeller hub and torque unit assembly of the type disclosed in these patents. From the engine frame E there extends an engine driven shaft 1 which supports and drives a propeller hub 2 which supports an accumulator 3 containing a piston 4 movable toward the right from the position shown under the action of compressed gas forced into the accumulator through a check valve 5. The space, 5 between the piston 4 and the fixed wall 6 of the accumulator, receives oil under pressure which forces piston 4 toward the left further to compress the gas to the left of the piston, thereby maintaining a supply of oil under pressure for 10 the purpose of feathering and unfeathering the propeller blades. Duct 7, through which oil flows into the accumulator, is controlled by a valve 8 to be described.

The hub 2 supports a plurality of blades 10, 20 each having its root journaled in bearings 11. Each blade is rotated about its root axis by a separate torque unit comprising a cylinder 12 attached to a blade root and having its upper end closed by cap 13 rotatably supported at its lower end by a bearing 14. Cylinder 12 cooperates with a piston 15 having external helical splines 16 cooperating with internal helical splines 17 of the cylinder 12 and having internal helical splines 18 of a relatively fixed member 19 supported by the hub 2. Pipes 20 and 21 lead respectively to the inner and outer ends of the cylinders 12 and are connected in a manner to be described with a distributing valve. The spiral splines are so constructed that inward movement of the piston 15 effects rotation of the cylinders 12 (clockwise looking outwardly) for the pitch increasing function; and outward movement of the pistons 15 effects rotation of the cylinders 12 in opposite direction for the pitch decreasing function. The cylinders 12 are each connected with a bevel gear segment 22, each meshing with a master gear 23 supported by a bearing 24 carried by the hub 2, thereby equalizing the pitch changing movements of the blades.

The hub 2 supports a plate 30 which, as shown in Fig. 3 is secured by tubular nut 31. The plate 30 and its cover 32 (Fig. 1) provides a reservoir for hydraulic fluid. The engine shaft 1 is surrounded by a non-rotatable tube 33 concentric with the shaft and with the nut 31 (Fig. 3). Tube 33 is provided with a tang 34 (Fig. 1) received by nuts between brackets 35 attached to engine frame E. The plate 30 and its cover 32 50 provide bearings which maintain the concen-

tricity of the tube 33, one of these bearings being shown at 36 in Fig. 3. Each bearing has a seal such as 37. Tube 33 provides an annular flange 38 which supports a plurality of shafts 39 each driven by a pinion 40 meshing with a ring gear 41 rotatably supported in any suitable manner by the sleeve 33. Ring gear 41 is provided with a handle or lever 41a which may be operated by a setting device which is under direct manual control or by one which is automatic in operation such as disclosed in the copending application of Joseph Stuart III, Serial No. 632,566, filed December 3, 1945.

Rotation of gear 41 by lever 41a effects rotary movements of shafts 39 for the purpose of obtaining blade pitch change. Each shaft 39 provides a screw 45 threaded into a grooved ring 46 slidably along the tube 33. Ring 46 receives a shoe 47 (Fig. 2) attached to a rod 48 guided for movement parallel to the shaft 1 by the plate 30. Shoe 47 connected by screw 49 with a bar 50 having a slot 51 which receives a shoe 52 provided by a pin 53 which swivels in a carriage 54 supported by rollers 55 slidable in ways provided by channel brackets 56 attached by screws 57 to a valve body 58 attached by screws 59 to the plate 30. The valve body 58 is part of a distributing valve unit 60 comprising a valve 61 slidable in a valve sleeve 62 having ports 63, 65 and 67 connected by annular grooves 64, 66 and 68 respectively with holes 69, 70 and 71 respectively. Hole 70 is connected in a manner to be described with a pressure pump. Hole 69 is connected with passages 21 and hole 71 is connected with passages 20. The position of valve 61 is determined by the position of carriage 54 which carries a roller 72 engageable with a lever 73 pivotally supported by pin 74 carried by a screw 75 attached to the valve body 58. Lever 73 is provided with a notch 76 receiving a pin 77 attached to the valve 61. Since centrifugal force acts upon the valve 61 as indicated by arrows 61a, Fig. 3, the lever 73 remains in engagement with the roller 72 while the propeller hub is rotated. Hence, no spring is required to hold the lever 73 against the roller 72. In the disclosed apparatus, when ring gear 41 is rotated counterclockwise by a setting device connected with lever 41a, an increase of blade angle is effected. Pinions 40 and shafts 39 rotate counterclockwise thereby causing the grooved ring 46 to move toward the left, thereby moving the carriage 54 toward the left. As roller 72 moves toward the left centrifugal force causes the valve 61 to move upwardly thereby connecting holes 70 and 69 which causes pressure fluid to flow through pipes 21 in order to force the piston 15 inwardly whereby blade pitch is increased. While the blades 10 are being rotated about their root axes in the direction of pitch increase the valve 61 is being returned to a balanced position closing ports 63 and 67 at which position the valve arrives when the demand for pitch increase has been satisfied. In order to accomplish this, the master bevel gear 23 is connected with a gear 80 (Fig. 5) which is retained by a plate 81 attached to the hub 2 and which meshes with a gear 82 pivotally supported by a screw 83 attached to a plate 84 supported by hub 2. Gear 82 meshes with gear 85 attached to a shaft 86 having a bearing and a boss 87 integral with the plate 84. Shaft 86 is connected with a coupling disc 88 connected by a screw 89 with a coupling disc 90 attached to a shaft 91 journaled in a bearing 92 carried by the plate 30 and retained by a nut 93 threaded on the bearing 92 as shown in Fig. 5. Shaft 91 is

provided with a helical groove 95 which receives a ball 96 carried by a member 97 which serves as a nut and travels along the helical or screw-threaded groove 95. Nut 97 provides a stud 98 passing through a slot 99 in bar 50 and retained by a nut 100. The back lash in the gears 82 and 85 is taken up by spring 101 having one end received by a notch 102 in the boss 87 and the other end received by notch 103 in the hub of the coupling disc 88. The spring 101 is initially wound up in order to spring-load the gears 80, 82 and 85. Coupling screw 89 passes through an elongated arcuate hole 90a in the disc 90, thereby providing for angular adjustment between the coupling disc 88 and 90.

When carriage 54 is in the position shown in Fig. 3 and in full section lines (Fig. 4), the valve 61 is in neutral position blocking ports 63 and 67 so that the torque units will not operate. One set of conditions which places valve 61 in neutral position, is that which exists when screw 49 and stud 98 are located as shown in Fig. 4. These are the conditions for minimum positive or maximum negative pitch. To decrease pitch negatively and increase pitch positively, gear 41 is rotated counterclockwise thereby causing ring 46 and carriage 41 to move left from the position shown in Fig. 2. The demand for pitch increase, positively, may be such as to place screw 49 in position 49' and bar 50 in position 50' and carriage 54 in position 54' (Fig. 4). This will effect blade angle increase, positively, in the manner described. During blade angle increase, the master gear 23 rotates counterclockwise as indicated by arrow 23a in Fig. 1 or clockwise in Fig. 6 as indicated by arrow 23b. Therefore the shaft 86 will rotate clockwise in Fig. 6, thereby causing the screw 95 to rotate counterclockwise as indicated by arrow 95a when viewed from the direction of arrow 95b (Fig. 5). Therefore, while the blades 40 are being rotated to increase pitch, the nut 97 will be moving down in Figs. 4 and 5 thereby carrying the stud 98 to the position 98' which causes the carriage 54 to be brought back into position shown in full lines in Fig. 4 thereby returning the valve 61 in balanced position. If the movement of ring 46 had been such as to cause the screw 49 to move to 49'', the carriage 54 would have been moved further than 54' thereby demanding a greater blade angle change which would cause the stud 98 to move to 98'' before the valve 61 is returned to balanced position. It is therefore apparent that for every position of the ring 46 there is a definite blade angle. Consequently, for every position of lever 41a, there is a definite blade angle position. The mechanism shown provides for adjustment of blade angle in a range of approximately 120°.

The flange 38 of sleeve 33 (Fig. 1) provides a stationary gear 110 meshing with a gear 111 which drives a pump P while the propeller hub is rotating. The outlet of pipe p of pump P is connected with the passage 70 of the distributing valve 60. Pipe p is connected by pipe p₁ with a pressure control unit PC connected by pipe p₂ with an accumulator control valve unit AV. The pressure control unit PC comprises a valve rod 130 having a dashpot head 131 received by a cylinder 132 connected with pipe p₁ and urged outwardly by centrifugal force acting in the direction of arrow 133 and by spring 134 in opposition to fluid pressure acting upon the lower (in Fig. 1) surface of a piston valve 135 received by a cylinder 136 and controlling a relief port 137. The inner end of cylinder 136 is connected by

pipe 138 with pipe 21 as shown also. Valve 135, being responsive to centrifugal force, causes the pressure in line p to increase as speed increases and this pressure is increased also when cylinder 136 receives pressure from the pipe 21 which is under pressure when there is a demand for pitch increase.

The unit PC includes also a minimum pressure control valve provided by a rod 140 having lands 141 and 142 for controlling the connection between port 137 and a discharge port 143. The rod 140 has a dashport head 144 engaged by a spring 145 located in a cylinder 146 connected with cylinder 132. The force of spring 145 is opposed by the fluid pressure acting upon the under (in Fig. 1) side of valve land 141. The pressure available in pipe p will be limited to a minimum value by movement of rod 140 to a position for connecting the ports 137 and 143, valve 135 having opened port 137. Up to a certain rotative speed of the hub, the pressure is limited to a minimum value in order that the accumulator will be fully charged within a short time even while the engine is operating at low speed. This minimum pressure is sufficient for the pitch-decreasing function of the torque units. As propeller speed increases, valve 135, being under control by centrifugal force, requires greater line pressure to cause the opening of the port 137. Therefore the pressure increases in pipe p above the minimum in order to make available, the pressures required for the pitch-increasing function which requires greater pressure with increase of speed.

While rod 140 of unit PC is shown parallel with rod 130 which is under the action of centrifugal force, it will be understood that rod 140 is not controlled by centrifugal force but is actually located at right angles to rod 130. The units PC and AV are fully described in the co-pending application of David A. Richardson, Serial No. 613,563, filed August 30, 1945.

For the understanding of the present invention, it is sufficient to state that the accumulator control valve unit AV has a check valve 150 which normally blocks flow from the accumulator 3 to pipe p_1 . When feathering is required, ring 46 is moved to the extreme left to cause a roller 151 (carried by a shoe 152 received in the groove of ring 46) to engage cam 153 on a lever 154 and to effect outward movement of said lever and of a rod 155 thereby opening the check valve 150. Pressure oil then flows from the accumulator to underside (in Fig. 1) of a piston 156 thereby effecting the opening of a valve 157 so that the accumulator may discharge to pipe p_1 through a by-pass around the check valve. During this discharge the valve 157 is held open by oil pressure against the underside (in Fig. 1) of a piston 158. As feathering is completed, the pressure differential between the pressure in pipe p_1 and the pressure against the underside of piston 158 decreases and spring 159 closes valve 157. Cam 153 having been momentarily contacted by roller 151 during movement of ring 46 to the extreme left, check valve recloses. Therefore discharge of the accumulator is prevented until it is desired to use accumulator pressure to assist in the unfeathering operation. This is effected by right (in Fig. 1) movement of ring 46 which effects momentary opening of check valve 150; and discharge of the accumulator into pipes p_1 and p takes place.

While the embodiment of the present invention as herein disclosed, constitutes a preferred

form, it is to be understood that other forms might be adopted, all coming within the scope of the claims which follow.

What is claimed is as follows:

1. Pitch-setting apparatus for a variable pitch propeller comprising a propeller hub, blades rotatably supported thereby for pitch-adjustment, an hydraulic servo-motor rotatable with the hub for angularly adjusting the blades said servo-motor having a cylinder, and pressure-fluid supply and control apparatus rotatable with the hub, said apparatus comprising a fluid-containing reservoir, a pump for forcing fluid from the reservoir to the servo-motor, a distributing valve unit comprising a body providing an inlet port connected with the pump and outlet ports connected respectively with the ends of said cylinder and a valve for controlling distribution from the inlet port to the outlet ports, a valve-positioning lever, supports respectively connected pivotally with the ends of said lever, a mechanism operatively connecting an intermediate portion of said lever with the valve, one of said supports being movable in one direction relative to the other support to effect movement of the valve from outlet-port-closing position in order to obtain a required blade-angle adjustment, the other of said supports being movable in the opposite direction relative to the first support in order to return the valve to outlet-port-closing position when the required adjustment of blade angle has been made, means responsive to the angular movement of the blades for so moving the second-mentioned support, and means non-rotatable with the hub for actuating the first-mentioned support.

2. Pitch-setting apparatus for a variable pitch-propeller comprising a propeller hub, blades rotatably supported thereby for pitch-adjustment, an hydraulic servo-motor rotatable with the hub for angularly adjusting the blades said servo-motor having a cylinder, and pressure-fluid supply and control apparatus rotatable with the hub, said apparatus comprising a fluid-containing reservoir, a pump for forcing fluid from the reservoir to the servo-motor, a distributing valve unit comprising a body providing an inlet port connected with the pump and outlet ports connected respectively with the ends of said cylinder and a valve for controlling distribution from the inlet port to the outlet ports, a valve positioning lever, supports respectively connected pivotally with the ends of the lever, a carriage pivotally connected with an intermediate portion of the lever, a cam follower supported by the carriage, a lever connected with said valve and providing a cam engaging said cam follower, one of said supports being movable in one direction relative to the other support to effect movement of the valve from outlet-port-closing position in order to obtain a required blade-angle adjustment, the other of said supports being movable in the opposite direction relative to the first support in order to return the valve to outlet-port-closing position when the required adjustment of blade angle has been made, means responsive to the angular movement of the blades for so moving the second-mentioned support and means non-rotatable with the hub for actuating the first-mentioned support.

3. Pitch-setting apparatus for a variable pitch propeller comprising a propeller hub, blades rotatably supported thereby for pitch-adjustment, a hydraulic servo-motor rotatable with

the hub for angularly adjusting the blades said servo-motor having a cylinder, and pressure-fluid supply and control apparatus rotatable with the hub, said apparatus comprising a fluid-containing reservoir, a pump for forcing fluid from the reservoir to the servo-motor, a distributing valve unit comprising a body providing an inlet port connected with the pump and outlet ports connected respectively with the ends of said cylinder and a valve for controlling distribution from the inlet port to the outlet ports, a valve-positioning lever, supports respectively connected pivotally with the ends of said lever, a mechanism operatively connecting an intermediate portion of said lever with the valve, one of said supports being a shoe movable in one direction relative to other support to effect movement of the valve from outlet-port-closing position in order to obtain a required blade-angle change, the other of said supports being movable in the opposite direction relative to the shoe in order to return the valve to outlet-port-closing position when the required adjustment of blade-angle has been made, means responsive to the angular movement of the blades for so moving the second mentioned support, a ring non-rotatable with the hub and having a groove for receiving said shoe, and means non-rotatable with the hub for laterally moving the ring.

4. Pitch-setting apparatus for a variable pitch propeller comprising a propeller hub, blades rotatably supported thereby for pitch-adjustment, an hydraulic servomotor rotatable with the hub for angularly adjusting the blades said servo-motor having a cylinder, and pressure-fluid supply and control apparatus rotatable with the hub, said apparatus comprising a fluid-containing reservoir, a pump for forcing fluid from the reservoir to the servo-motor, a distributing valve unit comprising a body providing an inlet port connected with the pump and outlet ports connected respectively with the ends of said cylinder and a valve for controlling distribution from the inlet port to the outlet ports, a valve-positioning lever, supports respectively connected pivotally with the ends of said lever, a mechanism operatively connecting an intermediate portion of said lever with the valve, one of said supports being movable in one direction relative to the other support to effect movement of the valve from outlet-port-closing position in order to obtain a required blade-angle adjustment, the other of said supports being a nut which is movable in the opposite direction relative to the first support in order to return the valve to outlet port closing position, rotatably supported screw engaged by said nut which, being pivotally connected with said lever, is non-rotatable relative to the screw, means for rotating the screw in response to angular movement of the blades in order to move the nut and thereby to return the valve to inlet-port-closing position when the required adjustment of blade angle has been made, and means non-rotatable with the hub for actuating the first-mentioned support.

5. Pitch-setting apparatus for a variable pitch propeller comprising a propeller hub, blades rotatably supported for pitch-adjustment, an hydraulic servomotor rotatable with the hub for angularly adjusting each blade, each servo-motor having a cylinder and a double acting piston, a master gear effecting the equal movement of all blades, pressure-fluid supply and control apparatus rotatable with the hub and adapted to rotate the blades in either direction, said appa-

ratus comprising a fluid-containing reservoir, a pump for forcing the fluid from the reservoir to either side of the servo-motors, a distributor valve-unit for controlling the distribution of fluid to one side or the other of the servo-motor pistons, means for moving the valve from an equilibrium position to a position admitting fluid to either side of the servo-motor pistons in order to obtain a required blade-angle adjustment, and means interengaging with the master gear and responsive to movement of the blades for returning the valve to the equilibrium position, the means for moving the valve comprising a remotely shiftable support, a lever connecting the support with the valve at an intermediate part of the lever, a nut and screw supporting the other end of the lever, said interengaging means being adapted to shift the last named support.

6. Pitch-setting apparatus for a variable pitch propeller comprising a propeller hub, blades rotatably supported for pitch-adjustment, an hydraulic servomotor rotatable with the hub for angularly adjusting each blade, each servo-motor having a cylinder and a double acting piston, a master gear effecting the equal movement of all blades, pressure-fluid supply and control apparatus rotatable with the hub and adapted to rotate the blades in either direction, said apparatus comprising a fluid-containing reservoir, a pump for forcing the fluid from the reservoir to either side of the servo-motors, a distributor valve-unit for controlling the distribution of fluid to one side or the other of the servo-motor pistons, means for moving the valve from an equilibrium position to a position admitting fluid to either side of the servo-motor pistons in order to obtain a required blade-angle adjustment, and means interengaging with the master gear and responsive to movement of the blades for returning the valve to the equilibrium position, the means for moving the valve comprising a cam carried lever pivotally supported and articulated to the valve so as to respond to centrifugal force, a manually movable cam follower normally engaging the cam carried lever for opposing valve movement by centrifugal force, and a differential lever connected at an intermediate point with said cam follower, and one end of said differential lever being mechanically connected for movement by said master gear and interengaging means.

7. Pitch-setting apparatus for a variable pitch propeller comprising a propeller hub, blades rotatably supported for pitch-adjustment, an hydraulic servomotor rotatable with the hub for angularly adjusting each blade, each servo-motor having a cylinder and a double acting piston, a master gear effecting the equal movement of all blades, pressure-fluid supply and control apparatus rotatable with the hub and adapted to rotate the blades in either direction, said apparatus comprising a fluid-containing reservoir, a pump for forcing the fluid from the reservoir to either side of the servo-motors, a distributor valve-unit for controlling the distribution of fluid to one side or the other of the servo-motor pistons, means for moving the valve from an equilibrium position to a position admitting fluid to either side of the servo-motor pistons in order to obtain a required blade-angle adjustment, and means interengaging with the master gear and responsive to movement of the blades for returning the valve to the equilibrium position, the interengaging means comprising a gear train meshing with the master gear, a relatively movable nut and screw driven by the master gear, and

differential leverage means connecting the nut with the said distributor valve.

8. Pitch-setting apparatus for a variable pitch propeller comprising in combination, a hub, a plurality of blades journalled in said hub for pitch shifting movement, a fluid pressure source provided by said hub for altering the pitch position of the blades, fluid servo-motors actuating each blade, a master gear effecting equalized pitch change movement of all of the blades, a distributor valve for connecting the fluid pressure source with all of the servo-motors, and means for shifting the distributor valve in either direction from an equilibrium position for actuating the servo-motors in reverse directions to effect a desired blade angle change, said shifting means including a cam-carrying lever articulated to said distributor valve and a cam manually movable from a point outside of the propeller for resisting movement of the valve by centrifugal force from the equilibrium position, and follow-up means including a gear train meshing with the master gear

for returning the distributor valve to the equilibrium position when the blades shift in angular position to the selected angle determined by the said manually movable cam.
